(57) **CLAIM**

The ornamental design for a lighting fixture, as shown and described.

DESCRIPTION

FIG. 1 is a perspective view of a lighting fixture comprising the new design;

FIG. 2 is a front elevational view thereof;

FIG. 3 is a left side elevational view thereof, a right side elevational view being a mirror image thereof; and,

FIG. 4 is a top view thereof, a bottom view being a mirror image thereof.

In the drawings figures, the lighting fixture is shown broken away to depict indeterminate length.
